US00D506702S

(12) United States Design Patent (10) Patent No.: **US D506,702 S**
Fan (45) Date of Patent: **** Jun. 28, 2005**

(54) SELF WATERING RESERVOIR

FR 1.024.483 1/1953
GB 2240250 7/1991

(76) Inventor: **Jianhua Fan**, 5800 Maudina Ave., Apt. C-2, Nashville, TN (US) 37209

* cited by examiner

(**) Term: **14 Years**

(21) Appl. No.: **29/171,266**

Primary Examiner—Stacia Cadmus
Assistant Examiner—Mimosa De

(22) Filed: **Nov. 19, 2002**

(57) CLAIM

(51) LOC (8) Cl. **11-02**

The ornamental design for self watering reservoir, as shown and described.

(52) U.S. Cl. **D11/143**

DESCRIPTION

(58) Field of Search D11/143, 144,

D11/145, 148, 152–154; 47/65.5, 66.6,
67, 68, 70, 71, 79, 81; 206/423; 248/27.8
